PRESSURE FOUNTAIN CLEANING SPONGE

Filed May 24, 1949

UNITED STATES PATENT OFFICE

2,501,289

PRESSURE FOUNTAIN CLEANING SPONGE

Marvin Flournoy Orndorff, Alexandria, Va.

Application May 24, 1949, Serial No. 95,120

2 Claims. (Cl. 15—130)

1

This invention relates to a cleaning implement, and more particularly to a pressure supply cleaning sponge, and it consists of the construction, arrangements and combinations herein described and claimed.

It is an object of the invention to provide a cleaning sponge wherein a handle element for supplying the cleaning fluid to the sponge element is effectively secured to the sponge member without the necessity of employing undesirable metallic parts which might come into contact with a surface being cleaned.

It is a still further and important object of the invention to provide a handle, one end of which is closed, the handle being flattened, defining a discharge nozzle for accommodation within a flexible socket means fixed to a cleaning element, such as a sponge, one flat face of the nozzle having an opening for discharge of a cleaning fluid into the sponge.

A still further important object of the invention is the provision of a cleaning sponge having means for securing of the handle which will discharge water or other cleaning fluid into the sponge and in which a second sponge member may be adhesively secured above and to the first sponge member, the sponge members being of different density so that various types of cleaning may be accomplished with a single cleaning implement, said handle element being reversible so as to discharge a cleaning fluid into either one of the sponge members.

Additional objects, advantages and features of invention will be apparent from the following description, considered in conjunction with the accompanying drawings, wherein:

Figure 1 is a perspective view of the cleaning implement;

Figure 2 is a plan view of the main body member of a handle attaching means, before assembly;

Figure 3 is a plan view of one of the elements which is cooperable with the main body element in forming a socket for reception of a fluid discharge handle;

Figure 4 is a longitudinal sectional view from the line 4—4 of Figure 1;

Figure 5 is a perspective view of a dual sponge cleaning element;

Fig. 5a is a fragmentary sectional view therethrough, illustrating the relation of the discharge nozzle opening and discharge openings of the sponge members;

Figure 6 is a fragmentary view of a modified form of the handle; and

2

Figure 7 is a modified form of the discharge end of the handle member, and nozzle.

There is illustrated in Figures 1 and 5 a cleaning element generally designated by the reference character 10, which as here shown, embodies a cellulose sponge member 11 which may be of any desired shape, and here shown as substantially square, the corners of which are preferably rounded, as at 12. Medially of the sponge member 11 a fluid discharge opening 13 is formed vertically through the sponge, into which the cleaning fluid will discharge, as will be described.

A flexible socket generally indicated at 14 is adapted to be secured to one face of the sponge cleaning element, which consists of a main body member 15 of dimensions somewhat smaller than the sponge member 11, and preferably the member 15 has rounded corners 16. As clearly shown in Figure 2, the body member 15 has an elongated opening 17 extending from an edge 18 inwardly and beyond the medial center of the body member 15. The body member 15 is preferably formed of rubber so that a secure bond may be effected with the sponge member 11, as will be described. Upon opposite faces of the body member 15 a leather strip 19 is secured by means of rivets 21 which may be presented through suitable openings 22 of the body member 15 and openings 23 of the strips 19. The strips 19 are additionally secured to the body member 15 by a line of stitching 24 which extends longitudinally along the strips and across the rear end thereof. The strips 19 will be centrally located above the elongated opening 17, and each is formed with an opening 25 for discharge of a cleaning fluid. With the body member 15 secured to the strips 19 in the manner described, the strips 19 would be spaced apart forming an opening 26 into which a suitably shaped handle and discharge nozzle may be inserted, as will be described. The assembly thus formed is secured to a face of the sponge member by applying a suitable adhesive, such as a rubber cement, to a face of the body member 15 as well as the adjacent strip 19 presenting such faces to the sponge member 11 suitably aligning opening 25 with the opening 13 of the sponge member. The strip members 19 project outwardly beyond the sponge a short distance providing a sufficient flexibility to admit a discharge nozzle of a hollow handle 27, within the socket 14 as will be now described.

The handle 27 may be of any suitable length, one end of which is interiorly threaded for reception of a threaded portion of a control valve

28, the latter having a water inlet opening interiorly threaded and into which a common hose connection 29 may be secured. The other end of the handle 27 is reduced into a flat formation to define a discharge nozzle 27' of a size to be snugly received within the opening 26. The outer end of the flattened portion of the handle is closed by a metallic solder or other suitable substance indicated at 30. One wall of the flattened portion of the handle is provided with an opening 31 for discharging water or other cleaning fluid into the opening 13 so as to thoroughly saturate the sponge 11.

In use, with the handle secured within the socket, water or other cleaning fluid may be controlled by adjusting the valve 28 to the proper flow, water or other cleaning fluid passing through the opening 31 into the sponge element 11. The sponge element may be applied to the surface to be cleaned, and it will be apparent that due to the flexibility of the sponge and the main body 15 a flexibility is obtained between the handle and the sponge, so that the latter may be effectively applied to a surface to be cleaned, and without liability of having any metallic parts contact such surface.

Figure 5 illustrates a dual cleaning element, the parts previously described being the same, but in addition a sponge member 11' is adhesively secured above and to the body member 15, the strip member 19, as well as to the exposed surface of the sponge 11. The sponge 11' has a discharge opening 13' corresponding to the opening 13 of the sponge 11. When it is desired to use the sponge 11' in a cleaning operation, it is only necessary to withdraw the handle from the socket and reverse the position of the opening 31 of the handle so that it would be presented to the opening 25 of the next adjacent strip 19 for discharge into the sponge 11', as shown in Fig. 5a.

The sponge element 11' is here shown as formed of a denser sponge structure than the sponge 11, the differences in the sponge elements providing a varied cleaning surface for different characters of surfaces to be cleaned.

In Figure 6, the handle 27 is shown slightly offset upon its upper side to the nozzle portion, which shape may be desirable in certain situations.

In Figure 7, a modified form of discharge open-

ing in the nozzle portion of the handle is disclosed, and in this instance a series of small apertures 31' are formed extending in longitudinal rows so that water will be discharged into the body of the sponge as well as into the openings 13 or 13' of the sponges.

The device has been effectively employed in the cleaning of automobiles, although the invention is not necessarily limited to such use, and while I have shown and described a preferred form of the invention, this is by way of illustration only and I consider as my own all such modifications in construction as fairly falls within the scope of the appended claims.

15 What I claim:

1. A pressure supply cleaning implement comprising a cellulose flat sponge member formed with a medially disposed vertical opening, a flexible socket member adhesively secured to one flat face of the sponge member, said socket comprising a flat main body member having an elongated opening formed therein opening upon one edge of the main body member, a flexible strip member secured upon opposite sides of the main body member and centrally positioned over said elongated opening and defining a passage, each of said flexible strip members having an opening aligned with the vertical opening in the sponge, an elongated flat nozzle removably secured within said passage, said nozzle having a closed end and a discharge opening aligned with an opening of one of the flexible strips and the opening in the sponge, and a liquid supply handle operatively connected to said nozzle.

35 2. The structure of claim 1 wherein said flexible strips project beyond the edge of the sponge being spaced apart and unattached at the edges of the strips to facilitate entrance of said nozzle.

MARVIN FLOURNOY ORNDORFF.
